Charles Wolff, Cincinnati Ohio.
Letters Patent (Design No. 109) dated 21st Aug 1847.

The schedule referred to in these Letters Patent and making part of the same.

To all whom it may concern. Be it known that I,
Charles Wolff of Cincinnati Hamilton County and State of Ohio have invented a new ornamental design for stones and I do hereby declare that the accompanying drawing is an exact description of the same ornamental parts of the stone.

What he claims as original and as his own invention is the general design and combination of the several ornamental parts to be made from the pattern, which the accompanying duplicate drawing represents but do not claim to be the inventor of any part of the stone itself. All of which is respectfully submitted

Albert Heuck
Augustus Peters.

as those below and also ornaments are even, (though on the other side of this stone it ornaments a solid panel.) All three of the plates described are composed of a bouquet of flowers, and leaf work, the panel near the top right corner is composed of scroll & leaf work, and is solid as at h but on the other side plate of this stone forms a door for the fireplace.

We have thus described the ornamental designs which we wish to Patent, and do hereby claim the exclusive right to the same for the above plates, as we have said them cut and displayed them.
